UNITED STATES PATENT OFFICE

ARTHUR J. COUGHTRY, OF BETHLEHEM, PENNSYLVANIA.

COUNTERSINKING MACHINE.

1,424,988.

Specification of Letters Patent. Patented Aug. 8, 1922.

Application filed April 9, 1920. Serial No. 372,407.

To all whom it may concern:

Be it known that I, ARTHUR J. COUGHTRY, a citizen of the United States, and a resident of Bethlehem, in the county of Northampton and State of Pennsylvania, have invented a certain new and useful Countersinking Machine, of which the following is a specification.

This invention has for its object a machine for simultaneously performing a plurality of like operations on the work and provided with means for quickly spacing the tools to conform to the spacing of the work as holes to be bored, reamed or counterbored, which machine is particularly simple and compact in construction, highly efficient and rapid in its operation and readily shiftable as a unit from one location to another. As the machine here illustrated is especially adapted for countersinking holes which are spaced approximately equidistant apart, such as the punched rivet holes in large plates used in ship building, I have for convenience and brevity, referred to it throughout the specification and claims as a countersinking machine, but obviously it may be used for other operations, that is, tools other than countersinking tools may be attached to the machine.

The invention consists in the novel features and in the combinations and constructions hereinafter set forth and claimed.

In describing this invention, reference is had to the accompanying drawings in which like characters designate corresponding parts in all the views.

Figure 1 is an end view of an apparatus embodying my invention, the countersinking machine proper being shown in side elevation.

Figure 2 is an enlarged side elevation, parts being omitted of the countersinking machine.

Figure 3 is a sectional view on line 3—3, Fig. 2.

Figure 4 is a plan view of parts seen in Fig. 3, parts being omitted.

Figure 5 is a fragmentary plan view, parts being omitted, taken approximately on the plane of line 5—5, Figure 2.

Figure 6 is an enlarged sectional view taken on the plane of line 6—6, Fig. 4, the driving belt being omitted.

Figure 7 is an end view of the machine and carriage therefor looking to the left in

Fig. 1, the arches of the supporting frame being omitted.

Figure 8 is an enlarged sectional view of the main supply valve.

Figure 9 is a plan view, partly broken away of the supporting frame, the plate on which the machine is to operate, being also shown.

This countersinking machine comprises generally, a frame, a plurality of tool carriages supported by the frame, tool spindles journaled in the frame, the carriages being movable relatively to each other to space the tools to conform to the spacing of the holes to be bored or countersunk, driving means for the spindles, and means for shifting the carriages to space the tool spindles without disconnecting the spindles from the driving means.

The frame 1 may be of any suitable form, size and construction, it being here shown as formed with an angular horizontal guideway 2.

3 are the tool carriages which are here shown as arranged parallel to each other and mounted to shift relatively to each other to space the tools and maintain their parallel relation. All of the carriages shift relatively to each other except the first, and the others shift uniformly increasing distances. That is, assuming that the tools are spaced two inches apart and a spacing of three inches is desired, the second tool will be shifted one inch and the third tool two inches, the fourth three inches, the fifth tool four inches, the sixth, five inches, etc. As here illustrated the carriages are formed with flanges 4 on their upper sides which bear at 5 against the downwardly facing surface of the guideway 2 and which are formed with angular flanges 6 at their free edges slidably interlocking in a groove portion 7 of the guideway 2.

The carriages 3 are also formed with flanges 8 at their lower ends opposed to the flanges 4. In other words, in the illustrated form of my invention, each carriage 3 is in the form of a wide channel member and one of the flanges as the upper flange is formed with a downwardly turned lip or flange 6 for engaging the groove 7. The upper side of the channel member coacts with the frame 1 to support the carriage. 9 designates the tool spindle which extends vertically through the flanges 4 and 8, and 10 are

- chucks of any suitable construction on the spindles 9 below the carriages 3 for carrying suitable tools as countersinking tools 11. The first carriage is held from shiftable movement as will be hereinafter described. The spindles 9 may be of any suitable form, size and construction and as here shown each is mounted to move axially to feed the countersinking tools into the work, and is composed of a plurality of sections as upper and lower end sections 12 and 13 and the intermediate section 14 which is connected to the sections 12 and 13 by universal joints 15, 16 of any suitable construction. The upper sections 12 extend above the carriages and into the frame 1 to coact with the driving means and the lower sections extend through bearings 17 carried by the lower flanges 8 of the carriages 3.
- 20 The mechanism for spacing the carriages uniformly increasing distances as here shown, operates to move the carriages simultaneously so that they maintain their parallel relation with each other and also 25 their equidistant spacing but at a greater or less distance apart and said mechanism as here shown, comprises lazy tongs 18, the elements of which are pivoted at their intersections at 19 to the carriages respectively.
- 30 One of the end links 20 of the lazy tongs is rigidly connected to a hand lever 21 by means of which the lazy tongs are operated to fold and extend the same in order to move the carriages 3 along the guide of the 35 frame 1. Obviously, by moving the handle lever 21 in one direction or the other all the carriages except one, will slide along the guideway 2 and hence adjust the spacing of the tools 11.
- 40 The driving means for the spindle as here shown, includes an actuator common to all of the spindles as a belt 22 running over wheels 23 mounted at opposite ends of the frame 1, one run of the belt engaging 45 wheels 24 on the upper ends of the spindles 12. One of the wheels 23 is mounted on a vertical drive shaft 25 journaled in the frame and in an aligned opening in an offset portion 26 of the first tool carriage, the 50 shaft holding the first carriage from shifting. This shaft is connected to a suitable motor of any desired type here shown as carried by a bracket 27 on the frame 1.
- 55 The belt 22 is here shown as a sprocket chain and the wheels 23 and 24 as sprocket wheels. The spindles 9 slide axially in the sprocket wheels 24 during the feeding of the spindles 9 vertically.
- 60 Preferably, this feed actuating means comprises a piston 28 on the lower section 13 of each spindle, the piston being movable in a cylinder 29 carried by the bearing 17 for the sections 13 and a supply pipe 30 for a motive fluid having extensible and shiftable branches 31 leading to the cylinders.
- The main supply pipe 30 is provided with a suitable valve 32 therein, Fig. 8, and each of the branches is also provided with a valve 33. Each of the branches as here shown, include sections associated respectively with the cylinders 29 and the main supply pipe 30 and connected together by a flexible pipe 34. The movement of each piston 28 by the motive fluid is against a spring 35, Fig. 3, located in the cylinder 29 between the piston 28 and the lower head of the cylinder. This spring withdraws the spindles upwardly when the motive fluid is cut off by closing the valve 32.
- In order that the spindles may center themselves automatically, the bearings 17 are mounted to shift slightly, said bearings extending through holes 36 in the lower flanges 8, of larger size than the bearings of the carriages 3, and the bearings are also constructed to engage upper and lower faces of the flange 8, and as here shown the lower head of each cylinder 29 engages the upper face of the flange 8 and a nut 37 threading on the lower end of each bearing 90 presses against the lower face of the flange 8. Usually suitable anti-friction bearings 38 are interposed between the lower head of the cylinder and the upper face of the flange 8 and between the nut 34 and the lower face of said flange.
- In ship building the holes in the plates 39 to receive the rivets are punched in the blank approximately equidistant apart although there are slight variations in the spacing and by reason of mounting the lower ends of the spindles so that they can shift said spindles can shift and permit the tool to center itself in the holes.
- The frame 1 is supported or suspended from the main carriage 40 by a swivel connection as a rod 41 extending through the vertical bearing 42 fixed to the frame 40, and fixed at its lower end to a bracket 43 secured to the frame 1 centrally thereof. A nut 44 threads on the upper end of the rod and holds the same from endwise movement. The carriage 40 is provided with wheels or rollers 45 which move along overhead tracks 46 on an overhead truck 47 which truck is provided with rollers 48 at their ends movable along tracks 49 supported by suitable framing or legs 50. The tracks 46 and 49 are here shown as in the form of I-beams, the rollers 45 and 48 engaging upper and lower faces of lower flanges of the I-beams. The frame 1 is provided with suitable handles 51 by which it is shifted in any direction or turned about the axis of its swivel.
- In operation, the plate 39 having holes punched therein or the location of the holes marked thereon is placed upon a suitable bed 52 located under the overhead tracks. In operation, the operator takes hold of the handles 51 and by pushing or pulling there-

on moves the truck 47 along the tracks 49 and also moves the carriage 40 along the tracks 46 until the tool carriage 1 is at any desired starting point on the plate 6. By 5 operating the handle 21 the tool carriages can be spaced a required distance apart to conform to the spacing of the holes to be bored or to be countersunk.

The motor which is running constantly 10 in the operation of the machine, rotates the tool spindles and the pressure of the motive fluid in the pistons 28 feed the tool spindles axially into the work. When such holes are being countersunk the tools 11 enter the 15 holes and the spindles center themselves owing to the sliding bearing 17 on the lower ends of the spindle.

When the operation is completed the valve 32 is closed permitting the springs 35 to 20 withdraw the tools from the holes. The frame 40 is then shifted along the tracks 46 to another set of holes and the operation is repeated.

When a transverse row of holes has been 25 countersunk, the tool carriage 1 is moved about its swivel 41 to position the tools so that they stand in a row lengthwise of the sheet and the operation repeated, and during the shifting from one location to the 30 other, lengthwise of the sheeting, the truck frame 47 moves on its rollers 48 along the tracks 49.

My invention is particularly applicable for counterboring holes on plates used in 35 ship construction, and as will be obvious to those skilled in the art, such holes can be counterbored in a much less time than by the methods and machines now used.

What I claim is:

- 40 1. In a countersinking machine, the combination of a frame, tool carriages mounted on the frame and movable toward and from each other to space the same apart, tool spindles mounted in the carriages, the 45 spindles being mounted to adjust themselves radially whereby each spindle centers itself independently of the other spindles, means common to all the carriages to simultaneously move them along the frame to vary the 50 spacing of the tools, and driving means for the spindles, substantially as and for the purpose specified.
2. In a countersinking machine, the combination of a frame, tool carriages mounted 55 on the frame and movable toward and from each other to space the same apart, tool spindles mounted in the carriages, the spindles being mounted to adjust themselves radially whereby each spindle centers itself 60 independently of the other spindles, means common to all the carriages to simultaneously move them along the frame to vary the spacing of the tools, and driving means for the spindles, substantially as and for the purpose specified.
3. In a countersinking machine, the combination of a frame, tool carriages mounted on the frame and movable toward and from each other to space the same apart, tool spindles mounted in the carriages, means common to all the carriages to simultaneously move them along the frame to vary the spacing of the tools, and driving means for the spindles, the spindles being shiftable axially relatively to the driving means 65 toward and from the work, substantially as and for the purpose set forth.
4. In a countersinking machine, the combination of a frame, tool carriages mounted on the frame and movable toward and from each other to space the same apart, tool spindles mounted in the carriages, the spindles being shiftable axially relatively to the driving means toward and from the work, and also having an adjusting movement radially in all directions whereby each 70 spindle centers itself relatively to the work independently of the other spindles, substantially as and for the purpose described.
5. In a countersinking machine, a frame, a plurality of tool carriages mounted on the frame and movable toward and from each other relatively to each other to space the same apart, tool spindles mounted in the carriages, the spindles including upper and lower sections and intermediate sections 75 connected by universal joints to the upper and lower sections, driving means connected to the upper sections and the upper sections being movable axially relatively to the driving means, the lower sections being mounted to have a centering movement radially in all 80 directions independently of each other, means common to all the carriages for simultaneously moving them along the frame to space the tools, and means for feeding the spindles axially toward and from the work, substantially as and for the purpose specified.
6. A machine of the class described comprising carriages having openings therein, a plurality of tool spindles extending through the openings, bearings for the spindles in the openings, each bearing being of less diameter than the opening in the carriage, means for engaging the carriage to hold said carriage from axial movement whereby each bearing is shiftable radially relatively to the carriage in all directions to center the tool relatively to the hole to be countersunk independently of the other spindles, and means common to all the carriages for spacing them apart, substantially as and for the purpose set forth.

In testimony whereof, I have hereunto signed my name, at Bethlehem, in the county of Northampton, in the State of Pennsylvania, this 31st day of March, 1920.

ARTHUR J. COUGHTRY.
